UNITED STATES PATENT OFFICE

144,417

DESIGN FOR A CRIBBAGE BOARD

Ralph T. Rycroft, Kenmore, N. Y.

Application October 1, 1945, Serial No. 122,451

Term of patent 14 years

(CL. D34—5)

To all whom it may concern:

Be it known that I, Ralph T. Rycroft, a citizen of the United States, residing at Kenmore, in the county of Erie, State of New York, have invented a new, original, and ornamental Design for Cribbage Boards, of which the following is a specification, reference being had to the accompanying drawing, forming part thereof.

I claim:

The ornamental design for a cribbage board, as shown.

RALPH T. RYCROFT.
